UNITED STATES PATENT OFFICE.

ERNEST SIDWELL, OF COVENTRY, ENGLAND.

AIR-COOLED INTERNAL-COMBUSTION ENGINE USED ON MOTOR-BICYCLES.

1,092,328.

Specification of Letters Patent. Patented Apr. 7, 1914.

Application filed April 25, 1913. Serial No. 763,639.

To all whom it may concern:

Be it known that I, ERNEST SIDWELL, a subject of the King of Great Britain, residing at Coventry, in the county of Warwick, England, have invented certain new and useful Improvements in or Relating to Air-Cooled Internal-Combustion Engines Used on Motor-Bicycles and the like, of which the following is a specification.

This invention relates to air-cooled internal combustion engines used on motor cycles and the like having cylinders provided with radiating ribs or fins and it has for its object to provide improved means for cooling the cylinders and for shielding the hot parts.

Hitherto it has been proposed to surround the cylinder with wire coils, and according to this invention such coils are used, being specially shaped to lie between and otherwise engage the radiating ribs, and yet project sufficiently far all around the cylinder or cylinders to shield the user. Thus these coils may serve as a trouser guard easily applicable to existing engines. Each coil may be continuous, being expanded when being put into place and being retained by its springy nature, but in some cases it is not possible to completely surround the cylinder owing to the presence of pipes or other irregular parts of the cylinder wall. In such cases each coil may contain a spring bow of the required length which will contract the coil and cause it to remain firmly in position.

In the accompanying drawings, Figure 1 is a central vertical section of part of the cylinder of an air cooled internal combustion engine showing two differently shaped coils. Fig. 2 is a similar view showing a modification. Fig. 3 is a plan view of a cylinder to which one of the constructions shown in Fig. 1 has been applied. Fig. 4 is a similar view showing the application of the invention to a multi-cylinder internal combustion engine. Fig. 5 is a plan view of a modification. Fig. 6 is a transverse view of the upper coil shown in Fig. 1. Fig. 7 is a plan view of the same. Fig. 8 is a view corresponding to Fig. 6 of the construction shown in Fig. 2, and Fig. 9 is a plan view of the same.

Like letters indicate like parts throughout the drawings.

The spring coils are in most cases continuous, consisting of wire of suitable section wound upon a mandrel to form a coil

of suitable transverse shape and length. The ends of the coil are in most cases connected together, the length being such that the coil has to be extended so as to spring around the cylinder as shown in Fig. 3, the natural spring of the coil causing it to contract and wedge in between the radiating fins as shown in Figs. 1 and 2. If desired the coil is slightly tapered in one direction as shown in Fig. 6 so as the better to wedge in between the fins, and one side of the coil may be enlarged as shown in the lower part of Fig. 1. Usually the ends of the coil are permanently fixed together, but the attachment may be such that the ends of the coil can be easily separated and re-joined when required. For a large cylinder, or a multi-cylinder casting as shown in Fig. 4, the coil is made of suitable length to go around the whole casting. If desired the coil may be arranged to slip upon each fin as shown in Figs. 2, 8 and 9, instead of wedging between the fins.

When the construction of the cylinder is such that a complete coil encircling it cannot be used a short coil as shown at A in Fig. 5 may be used, this being caused to grip the cylinder by the employment of a spring bow B arranged within the coil. The spring bow is of a contractile nature and causes the coil A to firmly grip the cylinder. It will be understood that the coil projects sufficiently far to shield the engine, in the case of a motor cycle protecting the rider's legs from contact with the hot cylinder. It also prevents control wires etc., from being damaged by contact with the hot cylinder walls. It will be clear that the coils completely surround the cylinder or cylinders and afford protection all around. It has previously been proposed to arrange a short length of coiled wire along one side of the engine, attaching the ends to suitable piping so as to shield the engine on one side. By the present invention protection is afforded all around the cylinder and no special attachments have to be made. Also the coils are continuous and are applicable to engines of different sizes without any alteration.

What I claim as my invention, and desire to secure by Letters Patent, is:

1. In combination, the cylinder of an air-cooled internal combustion engine, ribs on said cylinder, a spring coil engaging said ribs and surrounding said cylinder, and projecting sufficiently far to act as a shield substantially as set forth.

2. In combination, the cylinder of an air-cooled internal combustion engine, ribs on said cylinder, a spring coil engaging said ribs, and a spring bow contained within said 5 coil and adapted to grip said cylinder substantially as set forth.

3. In combination, the cylinder of an air-cooled internal combustion engine, ribs on said cylinder, an endless spring coil of taper 10 cross-section engaging said ribs and sur-

rounding said cylinder, and projecting sufficiently far to act as a shield substantially as set forth.

In testimony whereof I have signed my name to this specification in the presence of 15 two subscribing witnesses.

ERNEST SIDWELL.
